(57) **CLAIM**

The ornamental design for a sprayer wand, as shown and described.

DESCRIPTION

FIG. 1 is a perspective view of the sprayer wand embodying the new design.

FIG. 2 is a front view thereof.

FIG. 3 is a rear view thereof.

FIG. 4 is a right side view thereof.

FIG. 5 is a left side view thereof.

FIG. 6 is a bottom view thereof; and,

FIG. 7 is a top view thereof.

The figures show features in broken lines that do not form any part of the claimed design. The broken lines immediately adjacent the solid line portions of the design form the boundary of the design, with the broken lines forming no part of the claimed design. The sprayer wand is shown with symbolic breaks in its length. The appearance of any portion of the sprayer wand between the break lines forms no part of the claimed design.
